APPARATUS FOR AND METHOD OF KNITTING.

Application filed August 29, 1924. Serial No. 734,888.

Our invention relates to knitting machines adapted to knit plated fabrics and more particularly to the type in which stripes are produced by knitting two or more yarns of different colors together in such a way that while one yarn is being knit on the face of the fabric the others are being knit on the back of the fabric and reversing the positions of the yarns as desired. This may be termed striping by reversing the plating.

One object of our invention is to provide simple, improved and effective method and mechanism for producing horizontal stripes in hosiery by plating. By horizontal stripes we mean stripes that run with the courses.

For purposes of illustration we have shown our invention embodied in a seamless hosiery machine of the well-known Scott & Williams type.

20 In the accompanying drawings—

Fig. 1 is a side elevation in section through part of the head of a knitting machine showing the yarn guides and the levers controlling them;

25 Fig. 2 is a side elevation on a smaller scale of the pattern drums controlling the yarn guides;

Fig. 3 is a plan view of our yarn tension-changing means;

30 Fig. 4 is a front elevation of our yarn tension-changing means showing part of the wave of the needles;

Fig. 5 is a plan view of the throat plate showing the yarn guides in one radial position;

35 Fig. 6 is a similar plan view with the yarn guides in the reverse radial position;

Fig. 7 is an elevation of the hook of a needle showing how the yarns are fed to the needles when the yarn guides are in the position shown in Fig. 6;

40 Fig. 8 is a view similar to Figure 7 taken when the yarn guides are in the position shown in Fig. 5; and

45 Fig. 9 is a detail elevation of the mechanism controlling the movement of the striping pattern drum.

As is well understood, in plating the two different yarns are fed to the needles in such a way that one yarn will be regularly drawn to the face of the knitted fabric and the other yarn will be drawn to the back, both

yarns being preferably knit by every needle. It has heretofore been suggested that reverse plating or striping could be obtained by reversing the positions of the yarns being fed to the needles but this has never proved satisfactory and the devices heretofore suggested are not adapted for use in the modern circular knitting machine where the yarns pass through a throat which changes their direction just before going under the needles.

We have discovered that by putting some tension or drag on first one plating yarn and then the other, under certain conditions each plating yarn can be knit in first on one side of the fabric and then on the other. However, to make a mechanism which will reverse the plating yarns under any conditions, we combine with the tension-alternating feature a reciprocation of the yarn guides radially to the needle circle. The horizontal separation and the reversal of the yarns resulting from this movement of the guides is translated by the throat plate into peculiarly suitable positioning of the yarns as will be set forth in detail later, the whole operation combining to give a very effective striping. Of course stripes of numerous colors can be obtained by feeding a plurality of yarns as backing yarns, and bringing a different yarn to the face with each reversal.

Referring now to Fig. 1, of the drawings, the needles are indicated at N and the throat plate at 559, while the yarn feeding fingers over the throat plate are indicated at F. These yarn fingers F are pivoted on a crosspin 554 set in the upright portion of the latch ring 550, the latter being pivoted at a point 552 to the latch ring bracket 401. A separate yarn finger is used for each plating yarn and these fingers are made free to reciprocate radially to the needle circle by passing the crosspin through a slot s in each such yarn finger instead of the customary fitted hole. The yarn fingers can be raised out of feeding relation to the needles by means of the customary thrust bars 460 acting on the under side of the yarn fingers, whenever a change of yarns is desired. These thrust bars 460 are controlled by some of the usual cams on the main pattern drum 120 in any well known manner.

The alternation of the plating yarn fingers

between a position near the needle circle and one more distant is accomplished by the mechanism which will now be described. Fastened to the rear end of each plating 5 yarn finger by a screw 11^a is a vertical adjusting plate 11 to whose two ends are respectively attached a link 12 and a tension spring 13. This link and tension spring are each fastened at their other end to a vertical lever bar 14. The connections to each 10 end of link 12 are swivelled.

Fastened between a stud 15 on the upper 15 end of the lever bar 14 and a plate *p* on the upright portion of latch ring is a tension spring 16 tending to hold the lever bar and the yarn finger attached to it forward toward the needle circle. To provide accurate setting of the yarn finger in this forward position there is a screw 12^a mounted in the 20 adjusting plate 11 adapted to act as a stop by touching the upright portion of the latch ring just below the plate *p*. The method of attachment of the yarn finger to the lever bar just described, permits the yarn finger 25 or the whole latch ring to be raised out of action as usual. Each lever bar is fastened at its lower end to the upper arm of a bell crank lever 17 pivoted on a stud 18 mounted on a bracket *m* fastened to the frame of the 30 machine. Also mounted on this bracket, near the stud 18 is a shaft 19 which carries an auxiliary or striping pattern drum 20 and a ratchet wheel 21, the drum and wheel being adjustably fastened together, but free to 35 turn on the shaft 19. On the periphery of the ratchet wheel 21 are teeth, one of them being lower than the others. Inside this striping pattern drum is a spring-pressed friction brake *b* mounted on the shaft and 40 restraining the drum from accidental movement. On the surface of the drum are cams 22 each adapted to engage the adjustable foot 17^a of the lower arm of one of the bell crank levers 17. When a bell crank lever 45 rides up on one of the cams 22, the upper end of the corresponding lever bar 14 and the yarn finger connected to it is pulled away from the needle circle. By adjustment of the foot 17^a an accurate setting of the yarn 50 finger in the back position can be obtained. Thus, by alternating the cams 22 operating the two bell crank levers, the two striping yarn fingers can be kept in opposite positions and these positions reversed as desired. 55 The striping pattern drum is turned by a hook plate 23^a on one end of a racking pawl 23 engaging the teeth on the ratchet wheel 21. This racking bar 23 is swivelled at its 60 other end to a lever 24, pivoted on the frame of the machine. This lever 24 and the racking bar are reciprocated continuously by a heart shaped cam 25 located on the main drive shaft 32 beside the main bevel gear 31, the engagement between the cam and the 65 lever 24 being by means of a roller 26 on

one side of the end of the lever. This roller is held on the surface of the cam by a spring 27 stretched parallel to the racking pawl between the pawl and a guide plate 28 on the bracket *m*. There is a spring 23^b mounted 70 on the guide plate 28 tending to hold the racking pawl in engagement with the ratchet wheel. The racking pawl 23 lies in a slot in the guide plate 28 and is free to be lifted. The heart shaped cam 25 and the teeth on the ratchet wheel 21 are so cut that at each reciprocation of the racking pawl 23 the striping drum is advanced the length of one tooth on the ratchet wheel. The cams 22 on the striping pattern drum can be made of 80 any desired length, and since the main shaft 32 turns once for every revolution of the needle cylinder, it is possible to reverse the plating after every course or after several courses. 85

In order to stop the rotation of the striping drum when the machine is knitting parts of the stocking where striping is not desired, and for another purpose which will be described later, an idling lever 530 is mounted loose on the shaft 19. The foot of this lever 90 overlies the main pattern drum 120 and is adapted to be lifted by the cams 501 and 502. Projecting upward from this lever to a point just below the racking pawl 23 is an adjustable arm 531. When the idling lever 95 530 rides up on to a cam 501, this arm 531 is adapted to lift the racking pawl so that the plate 23^a will not engage any of the teeth on ratchet wheel 21. This lifting takes place as the needle cylinder begins to reciprocate to make the heel of the stocking. At the end of the heel the racking pawl is lowered to continue moving the ratchet wheel 21 from where it left off, the pattern thus being unbroken on the instep of the stocking in spite 100 of the insertion of the heel on the back. At the end of the striped pattern in the foot, the striping yarn fingers *F* are removed from action by the thrust rods 460 and the racking bar lifted by means of a cam 502 on the 105 main pattern drum. This cam is lower than cam 501 with the result that the racking pawl 23 will continue advancing the ratchet wheel 21 until it comes to the low tooth over which it idles until it is desired to again make 110 striped work. This results in always starting the striped pattern at the beginning of its cycle. 115

The idling lever 530 can also be employed to vary the striped pattern by intermittently 120 stopping the rotation of the ratchet wheel 21. The mechanism which operates the idling lever for this purpose is a toggle actuated by the usual quadrant or segment gear 75 pivoted on a shaft 76 on which the 125 main pattern drum 120 is mounted (see Fig. 9). This quadrant is actuated from a main drive gear (not shown) by a pitman 70, fastened to the quadrant by a pin 71, and is used amongst other things to actuate the pat- 130

tern chain. It is geared to make one complete reciprocation for every four revolutions of the needle cylinder. Mounted on the quadrant is a pin 77 held by a set screw 77^a. On the end of this pin is fastened one end of a short bar 532 with a slotted link 533 pivoted at the other end—this bar and link comprising the toggle.

From one side of the idling lever 530 projects a short pin 534 which lies in the slot 533^a in the slotted link 533. As the quadrant 75 swings away from the ratchet wheel 21 the bar 532 swings the slotted link up and when the pin 534 engages the bottom of the slot 533^a the idling lever is raised and clears the racking pawl from the teeth on the ratchet wheel. The racking pawl is thus made to idle over the ratchet wheel for one or more courses. It will be apparent that by adjusting the position of the dead center of the bar 532 and link 533 the racking bar can, for instance, be made to advance the ratchet wheel one tooth and miss the next, advance two teeth and miss the next two, advance three teeth and miss the next one, or advance one tooth and miss the next three, thus altering the number of revolutions of the needle cylinder required to complete one revolution of the ratchet wheel 21. If it is desired to rack every course the pin 534 is removed from the slot in link 533.

In practical knitting it is necessary to have some tension on the facing yarn but practically none on the backing yarn. We have discovered that it is possible to reverse the plating in certain cases by merely applying tension to the two plating yarns alternately, and feeding them to the needles from approximately the same point on the throat plate, but to make a machine which will reverse the plating under any conditions we prefer to combine the alternating of the tension with the yarn finger control mechanism above described. The tension changing mechanism which we are about to describe is peculiarly effective and simple.

Mounted on the upright portion of the latch ring is a bracket *a* carrying the yarn tensioning mechanism. Each yarn passes between two convex discs *d*—whose convex sides face each other—just before it goes to the toe of its yarn finger (see Fig. 4). Each pair of discs is mounted on a pin *b*, passing through the centre of the discs and the discs are held together by a compression spring *c* whose degree of compression can be adjusted by a thumb-nut *e*, mounted on the pin *b*. The discs are held from turning by a pin *f*, set in notches in the edge of the discs. Each pair of discs, thus mounted, would normally act as a drag on the yarn passing between the discs, but the two pairs of discs are made to release their yarns alternately thus enabling the machine to keep tension on the facing yarn by reversing the tension when

the two yarns are reversed. This is accomplished by the means which will now be described.

Pivoted from bracket *a* on the upright portion of the latch ring, is a curved arm *g* having a slanting edge facing the circumference of one of the discs of each pair. When this arm is swung up, the slanting face presses against the edge of one convex disc and pushing against the pressure of the compression spring *c*, tips this disc away from the other, opening a space between the two discs on one side of the pin *b*. The yarn being between the discs on the side of the discs thus opened, has the drag removed from it. In order to operate this tension releasing device, a wire *h* is hooked into the arm *g* at a point above the pivot centre of the arm. The wire passes to the rear of the machine, where it passes through the stud 15 on the upper end of the lever bar 14.

To maintain the proper relation between the lever bar 14 and the wire *h*, there is an adjustable collar *j* at the end of the wire *h* with a small tension spring *k* between the sleeve and the plate *p*. The lever bar is held towards the latch ring by a tension spring 16, this having the effect of keeping the arm *g* down and out of engagement with the discs.

The plating reversing mechanism operates in the following manner, whichever yarn is acting as the facing yarn being designated at *y*¹, and the yarn acting as the backing yarn as *y*². The striping pattern drum is brought into action by the idling lever 530 dropping off its cam 502 on the main pattern drum 120 and letting the racking pawl 23 engage the low tooth on the ratchet wheel 21. The racking pawl being in continuous reciprocation the striping pattern drum starts to turn. The two plating yarn fingers *F* are dropped into operative position by the thrust bars 460 dropping off their cams on the main pattern drum and the spring 13 pulling against the link 12 bringing the yarn fingers down into contact with the heel of the throatplate 559. The yarn finger whose bell crank lever 17 is on a cam 22 then assumes a position away from the needle circle, while the yarn finger whose bell crank lever is off its cam 22 goes to a forward position. For purposes of illustration we shall assume that the parts take positions shown in Fig. 5. The lever bar 14 which is drawn back pulls the wire *h* raising the arm *g* into engagement with the outer disc above it removing the drag on the backing yarn *y*² (see Fig. 4). The backing yarn *y*² after passing between its two separated discs *d* goes through the toe of its retracted yarn finger, diagonally over the throat plate, 559 to the corner of the throat 560 and at this point the yarn *y*² turns down to the needles *N* passing under the hooks of the needles beyond the

throat plate in the direction of rotation of the needle circle. The facing yarn however is put under tension by its two discs, and goes through the toe of its yarn finger which is in the forward position. In this way the yarn fingers achieve a horizontal separation of the yarns in a direction substantially radial to the needle circle. The facing yarn y^1 goes out to the throat and over it at a distance from the corner, after which it goes down to the needles, getting under the hooks before the backing yarn y^2 in point of time. From the position of the throat and the needle circle it will be apparent that the two yarns are under the hooks at different elevations as shown in Figs. 7 and 8—Fig. 7 corresponding to Fig. 6 and Fig. 8 corresponding to Fig. 5.

When the cams 22 on the striping drum 21 change alternation the plating yarn fingers reverse their positions in a manner which will be obvious and the arm g which was in engagement with its disc d drops down, releases the disc and puts a drag on its yarn, which now becomes the facing yarn y^1 . At the same moment the other arm g is raised and releases its yarn from tension. The yarn fingers have enough clearance above the throat plate to permit of the yarn which was facing yarn y^1 passing under the other yarn finger as it passes to the corner of the throat plate. The yarn which now feeds from the forward yarn finger of course goes over the throat at a distance from the corner 35 as the other yarn did before.

The operation of the device for varying the number of courses in each stripe will be obvious from the description already given.

It will be apparent that our invention is 40 applicable to all kinds of knitting machines. Where in the claims we refer to two yarns, it should be understood that we include the possibility of using any number of facing and backing yarns.

45 What we claim is:

1. In a knitting machine, plating reversing mechanism comprising a plurality of yarn fingers adapted to separate their yarns in a horizontal plane by reciprocation toward and from the needles, in combination with a throatplate over which the horizontally separate yarns pass to the needles, said throatplate being adapted to give the yarns different elevations as they approach the needles.

2. In a knitting machine, plating reversing mechanism comprising a plurality of yarn changing yarn fingers adapted to separate their yarns in a horizontal plane by reciprocation toward and from the needles, in combination with a throatplate over which the horizontally separate yarns pass to the needles, one of said yarns being guided to the needles by the corner of the throatplate and another at a distance from

the corner, thus giving the yarns different elevations as they approach the needles.

3. In a knitting machine, plating reversing mechanism having yarn fingers adapted to reciprocate toward and from the needles 70 in a horizontal plane in combination with tension means adapted to put a drag on each yarn alternately when the finger from which that yarn is coming is nearest the needles, and a throatplate adapted to separate the 75 yarns vertically as they pass over it to the needles.

4. In a circular knitting machine, plating reversing mechanism having a plurality of 80 yarn changing yarn fingers adapted to reciprocate radially to the needle circle and to separate their yarns in a horizontal plane, in combination with a throat plate over which the yarns pass to the needles, said throatplate being adapted to give the yarns 85 different elevations as they approach the needles.

5. In a circular knitting machine having a plurality of yarn-changing yarn fingers, 90 plating reversing mechanism including two of said yarn changing yarn fingers adapted to reciprocate radially to the needle circle, and to separate their yarns in a horizontal plane, in combination with a throat plate 95 over which the yarns pass to the needles, said throat plate being adapted to give the yarns different elevations as they approach the needles.

6. In a circular knitting machine having a plurality of yarn-changing yarn fingers, 100 plating reversing mechanism including two of said yarn changing yarn fingers adapted to reciprocate radially to the needle circle and to separate their yarns in a horizontal plane only, in combination with a throat 105 plate over which the yarns pass to the needles, said throat plate being adapted to feed the yarns to the needles at different elevations, the backing yarn being guided to the needles by the corner of the throat plate. 110

7. In a circular knitting machine, plating reversing mechanism having yarn changing yarn fingers adapted to reciprocate radially to the needle circle, a throat plate adapted to receive the yarns from the yarn fingers and feed them to the needles at different elevations, the backing yarn being guided to the needles by the corner of the throat plate, in combination with tension means adapted to put a drag on each yarn alternately when 120 the finger from which that yarn is coming is nearest the needles.

8. In a circular knitting machine, plating reversing mechanism comprising two yarn fingers adapted to reciprocate radially to the 125 needle circle, a throat plate adapted to receive the yarns from the yarn fingers and feed them to the needles at different elevations, in combination with tension means adapted to put a drag on each yarn alter- 130

nately when the finger from which that yarn is coming is nearest the needles, and unitary cam means controlling the reciprocation of said yarn fingers and the putting of tension 5 on the yarns.

9. In a circular knitting machine, plating reversing mechanism comprising yarn fingers reciprocable radially to the needle circle, each having in association therewith 10 means adapted to put a tension on the yarn in said finger when said yarn is acting as a facing yarn, in combination with a throat plate adapted to give said yarns different elevations as they approach the needles and 15 cam means controlling reciprocation of said yarn fingers.

10. In a circular knitting machine having pattern control means, plating reversing mechanism comprising yarn fingers reciprocable radially to the needle circle, each having in association therewith means adapted 20 to put a tension on the yarn in said finger when said yarn is acting as a facing yarn, in combination with a throatplate adapted to

give said yarns different elevations as they 25 approach the needles, cam means controlling the reciprocation of said yarn fingers and tension means, and ratchet means operating said cam means and controlled by the pattern control means.

11. A method of knitting plated fabrics comprising feeding two yarns through two yarn fingers at different distances from the needles with tension on one of said yarns, then passing said thus horizontally separated 35 yarns over a throatplate at substantially the same level whereby the yarns are fed to the needles at different elevations, and subsequently reciprocating the yarn fingers at right angles to the needles in a horizontal 40 plane, thereby reversing the feeding positions of the yarns, and simultaneously transferring the tension to the other yarn.

In testimony whereof we have signed our names to this specification.

ROBERT W. SCOTT.
ALBERT E. PAGE.
